UNITED STATES PATENT OFFICE.

WILLIAM MACKERT, OF READING, PENNSYLVANIA.

CHIMNEY-CAP.

SPECIFICATION forming part of Letters Patent No. 533,995, dated February 12, 1895.

Application filed March 28, 1894. Serial No. 505,890. (No model.)

To all whom it may concern:

Be it known that I, WILLIAM MACKERT, a citizen of the United States, residing at Reading, county of Berks, State of Pennsylvania, have invented certain Improvements in Chimney-Caps, of which the following is a specification.

My invention relates to certain improvements in chimney caps the main object of which is to provide a cheap and conveniently applied roof or covering for use in connection with the cap pieces which are directly supported upon the chimney.

The invention is fully described in connection with the accompanying drawings and is specifically pointed out in the subjoined claims.

Figure 1 is a sectional elevation of a complete chimney cap embodying my improvements, the section being taken on the line $x-x-x$ of Fig. 2. Fig. 2 is a plan view of the same with the roof plate removed but with the corner posts in position, one of which is shown in cross-section. A portion of one of the pieces C is broken away where the extensible connection with the adjacent piece is made. Fig. 3 is a plan view of a portion of the roof plate with one of the corner posts indicated in dotted lines.

30 A represents the top portion of a brick chimney which is shown formed in steps at the top as is frequently done.

B is a binding frame made up of a series of four strips which are extensibly connected 35 at either side of the chimney by means of bolts which pass through holes in one section or strip and engage a slot in the other, as indicated by the dotted lines in Fig. 1 which represent the lapping of two of the 40 strips, on the opposite side of the brick work.

C are cap pieces bearing upon the top of the chimney and similarly connected together in the same manner as the binding frame by means of bolts engaging the lapping portion c' of one piece and the slots c^2 of the adjoining piece so as to permit adjustment of both frame and cap to different sizes of chimneys. A depending flange c on these cap pieces is adapted to inclose the vertical 45 flange b on the binding frame B.

The cap pieces C are provided at each corner with tapering undercut projections c^3 which are adapted to engage and lock the feet d^4 of corner posts D so as to permit the latter to be readily connected to the cap 55 pieces. The top of these posts is formed with bolting lugs d' which are provided with slots d^2 extending diagonally inward from the corner, and upon these lugs are supported the roof plate F. The latter is provided at each 60 corner with slots f arranged at right angles to the slots d^2 in the corner posts, the object of this arrangement being to enable the same roof plate to be conveniently secured to posts located at different distances apart. By slotting the lugs d' and the plate F so that the slots intersect each other as shown it is evident that the bolt E will engage both so as to permit the convenient fastening of them together though the distances between the 70 posts vary considerably in both directions. Ornamental pieces G on top of the roof plate serve to cover the slotted openings in the latter.

The binding frame B serves to greatly 75 strengthen the top of the chimney and is at the same time adjustable to different sizes and forms a substantial support for the cap pieces C.

The posts D and roof plate F are by means 80 of my construction readily and firmly attached to the cap pieces being easily adjusted to correspond with the latter and each other regardless of all irregularities which may occur.

85

What I claim is—

1. In a chimney cap the combination with the extensible pieces C of corner posts D removably secured thereto and having bolting lugs d' at the top provided with diagonal slots d^2 and a roof plate having corner slots arranged at right angles to said slots in the post lugs and adjustably secured thereto, substantially as set forth.

2. In a chimney cap the combination with 95 the extensible pieces C of corner posts D removably secured thereto and having bolting lugs d' at the top provided with diagonal slots d^2 , a roof plate having corner slots arranged at right angles to said slots in the post lugs, 100

ornamental pieces G arranged to cover said slots and bolts engaging said slots to adjustably secure the parts, substantially as set forth.

5 3. In a chimney cap the extensibly connected binding strips B adapted to inclose the top of the chimney and having a vertical flange b, in combination with the extensibly connected cap pieces C having a depending

flange c inclosing said flange b of the binding strips, substantially as set forth.

In testimony whereof I affix my signature in presence of two witnesses.

WILLIAM MACKERT.
